UNITED STATES PATENT OFFICE.

LAURELL LA VERGNE LUGAR, OF YAKIMA, WASHINGTON.

DESIGN FOR A GOLF TEE.

Application filed August 17, 1926. Serial No. 18,771. Term of patent 7 years.

To all whom it may concern:

Be it known that I, LAURELL LA VERGNE LUGAR, a citizen of the United States, residing at Yakima, in the county of Yakima and State of Washington, have invented a new, original, and ornamental Design for Golf Tees, of which the following is a specification, reference being had to the accompanying drawing, forming part thereof.

In the drawing Figure 1 is a plan view of a golf tee, showing my new design; Figure 2 is a side view thereof; Figure 3 is a vertical sectional view on line 3—3 of Figure 1 and Figure 4 is an underside plan view.

I claim:

The ornamental design for a golf tee, as shown.
